(57) **CLAIM**

We claim the ornamental design for a luminaire, as shown and described.

DESCRIPTION

FIG. 1 is a perspective view of a luminaire.

FIG. 2 is a front view of the luminaire shown in FIG. 1.

FIG. 3 is a rear view of the luminaire shown in FIG. 1.

FIG. 4 is a right side view of the luminaire shown in FIG. 1.

FIG. 5 is a left side view of the luminaire shown in FIG. 1.

FIG. 6 is a top view of the luminaire shown in FIG. 1.

FIG. 7 is a bottom view of the luminaire shown in FIG. 1.

FIG. 8 is a perspective view of a luminaire.

FIG. 9 is a front view of the luminaire shown in FIG. 8.

FIG. 10 is a rear view of the luminaire shown in FIG. 8.

FIG. 11 is a right side view of the luminaire shown in FIG. 8.

FIG. 12 is a left side view of the luminaire shown in FIG. 8.

FIG. 13 is a top view of the luminaire shown in FIG. 8; and,

FIG. 14 is a bottom view of the luminaire shown in FIG. 8. The broken lines on the drawings depict portions of the luminaire that form no part of the claimed design.

1 Claim, 8 Drawing Sheets
